UNITED STATES PATENT OFFICE.

FRANK CREASON, OF RICHMOND, MISSOURI, ASSIGNOR OF ONE-HALF TO W. A. MULLIN.

CEMENT-BLOCK MOLD.

1,342,373.

Specification of Letters Patent.

Patented June 1, 1920.

Application filed July 10, 1919. Serial No. 309,809.

To all whom it may concern:

Be it known that I, FRANK CREASON, a citizen of the United States, residing at Richmond, in the county of Ray and State 5 of Missouri, have invented certain new and useful Improvements in Cement - Block Molds; and I do declare the following to be a full, clear, and exact description of the invention, such as will enable others skilled 10 in the art to which it appertains to make and use the same.

My invention has for its object to provide a simply constructed and inexpensive, yet a highly efficient and in every way desirable 15 mold for constructing cement building blocks of any required lengths and in such manner as to permit the formation of a continuous air channel in the blocks of each tier of the completed wall.

20 With the foregoing in view, the invention resides in the novel construction and arrangement of parts hereinafter fully described and claimed, the descriptive matter being supplemented by the accompanying 25 drawings which form a part of this application.

Figure 1 is a top plan view of a mold constructed in accordance with my invention.

Fig. 2 is a side elevation.

30 Fig. 3 is an end view.

Fig. 4 is a horizontal section on the plane of line 4—4 of Fig. 2.

Fig. 5 is a longitudinal section as indicated by the irregular line 5—5 of Fig. 1.

35 Fig. 6 is a transverse section on the plane of line 6—6 of Fig. 1.

Fig. 7 is a perspective view of one of the end forming members.

In the drawings above briefly described, 40 the numerals 1 and 1^a designate a plurality of parallel members which form the sides of the blocks and will therefore be herein-after referred to as side forming members. The outermost members 1^a are each formed 45 of a strip of sheet metal with its central longitudinal portion stamped inwardly to provide the inner side of the member with a longitudinal rib 2. Transverse bars 3 span the inwardly stamped rib forming portions 50 of the members 1^a and the edges of the latter may well be clenched around the ends of said bars as seen at 4. These bars are formed with openings 5 to receive tie rods 6 by means of which all of the side 55 forming members are clamped together, said

members having openings through which the rods pass as clearly shown in Fig. 6. One end of each rod may be provided with a crank 7 and the other end may be threaded at 8 through one of the openings 5. 60

The intermediate side forming members 1 are each formed of two strips 9 of sheet metal, the edges of one strip being clenched around the edges of the other as seen at 10, while the intermediate longitudinal portions 65 of both strips are stamped outwardly to provide longitudinal ribs 11. These ribs and the ribs 2 form longitudinal air circulating grooves in the opposite sides of the blocks. 70

Transverse end forming members 12 and 12^a extend between the side forming members, said members 12^a being located at the extreme ends of the mold while the members 12 are slidable into differently spaced relation, according to the length of the blocks to be constructed. Each member 12 consists of two H-shaped plates whose parallel 75 portions 13 contact with each other and have their edges clenched together at 14, while the connecting portions 15 of the plates are stamped outwardly to provide ribs. The edges of the connecting portions 15 abut the ribs 2 and 11 and the ends of the parallel 80 portions 13 bear against the side forming members 1 and 1^a above and below said ribs. In effect, notches are formed in the ends of the members 12 to snugly receive the ribs of the side forming members and slide along 85 said ribs as required. 90

The end forming members 12^a are each constructed of an outer H-shaped plate 13^a and an inner similarly shaped plate 13^b, the two being clenched together at their edges as seen at 14^a. The entire area of the 95 plate 13^a is located in the same plane, while the connecting portion 15^a of the inner plate 13^b is stamped to form a rib corresponding to the rib forming portions 15. The ends of the longitudinal side forming members 1 100 and 1^a are bent laterally to provide flanges 16, against which the end members 12^a abut, and the outermost of the tie rods 6 may well pass through said end members as shown for instance in Fig. 5. Similarly, the other 105 tie rods may extend through the end forming members 12 when the latter are spaced in such relation as to permit.

When forming blocks of exceptional length, the members 12 may be omitted be- 110

tween certain of the members 1 as seen at the bottom of Fig. 4, and sleeves 17 may then surround the tie rods 6 to hold the longitudinal members in properly spaced relation.

In operation, the entire mold is placed on a suitable pallet (not shown), the end forming members 12 are adjustable as required, and are clamped in place by tightening the rods 6 and the cement may then be poured into the mold. The surface of the blocks to be exposed when incorporated in a wall, may be finished in any preferred manner, but the suction system is by preference employed for this purpose and a suitable edging tool is used.

The device is of simple and inexpensive, yet efficient and durable construction, and is in every way desirable; and on account of the proven merit of the details disclosed, they are by preference followed. I wish it understood however that within the scope of the invention as claimed, numerous minor changes may well be made.

25 I claim:

1. In a cement block mold, a plurality of parallel longitudinal side forming members having longitudinal ribs on their sides, transverse end forming members extending between said side members and having notches in their ends receiving said ribs, said end members being slidable along said side members, and means for clamping said side members against said end members.

35 2. In a cement block mold, a plurality of parallel longitudinal side forming members having longitudinal ribs on their sides, transverse end forming members extending between said side members and each formed of two H-shaped plates with the parallel portions of one plate contacting with and clenched around the parallel portions of the other plate, and with the connecting portions of the two plates bowed outwardly, 40 the edges of said connecting portions abutting said ribs and the ends of said parallel portions bearing against said side members above and below said ribs, and means for clamping said side members and end members together.

45 3. In a cement block mold, a plurality of parallel longitudinal side forming members formed of sheet metal stamped to provide said members with longitudinal ribs, the 50 outermost of said side members having ribs

on their inner sides only and having transverse bars on their outer sides spanning their inwardly stamped rib-forming portions, said bars having openings and said side members being formed with openings 55 alined therewith, transverse end members extending between said side members and having notches in their ends receiving said ribs, and tie bolts passing through the aforesaid openings of said side members and said bars.

4. In a cement block mold, a plurality of parallel longitudinal side forming members formed of sheet metal stamped to provide said members with longitudinal ribs, the 60 ends of said side members being bent laterally to form flanges, end members extending between said side members and having notches in their ends receiving said ribs, said end members abutting said flanges, and 65 means for clamping said end members and said side members together.

5. In a cement block mold, a plurality of parallel longitudinal side forming members formed of sheet metal, each of the outermost of said members being formed of one strip of metal inwardly stamped to provide a longitudinal rib at its inner side, the other side forming members being each constructed of two metal strips clenched together at 80 their edges and stamped outwardly to provide both sides of said members with longitudinal ribs, transverse bars spanning the inwardly stamped rib forming portions of said outermost side forming members and 85 having openings; the several ribs having openings alined with those of said bars, tie rods passing through the alined openings, and transverse end forming members extending between said side forming members 90 and each formed of two H-shaped plates whose parallel portions are clenched together at their edges and whose connecting portions are stamped outwardly, the edges of said connecting portions abutting said 95 ribs, and the ends of said parallel portions bearing against said side forming members above and below said ribs, the ends of said side forming members being laterally bent to provide flanges against which the outermost of said end forming members abut.

In testimony whereof I have hereunto set my hand.

FRANK CREASON.
